(57) **CLAIM**

The ornamental design for a transmission line compact insulator and hardware assembly, as shown and described.

DESCRIPTION

FIG. 1 is a perspective view of the transmission line compact insulator and hardware assembly;

FIG. 2 is a front view thereof;

FIG. 3 is a left side view thereof, the right side view being a mirror image thereof;

FIG. 4 is a rear view thereof;

FIG. 5 is a top view thereof;

FIG. 6 is a bottom view thereof;

FIG. 7 is an enlarged perspective view of a region “7” of FIG. 1; and,

FIG. 8 is an enlarged front view of a region “8” of FIG. 2. The broken lines shown in the drawings are for the purpose of illustrating portions of the transmission line compact insulator and hardware assembly that form no part of the claimed design.
